PERFORATOR KNIFE

Application filed November 21, 1928. Serial No. 320,939.

My invention relates to oil well equipment and more particularly to casing perforators and is an improvement on my prior invention, application entitled Double casing perforator, No. 256,178, filed February 23, 1928.

After a well has been drilled, a casing called the "water string" is inserted therein, and there is extended in this water string a casing known as the "oil string". The oil string is provided with a screen pipe which extends through the oil sands and the screen pipe is adapted for the purpose of straining from the inward seeping oil gravel and sand which might injure the oil pump. The screen pipe is either formed prior to the installation of the oil string or else the oil string is perforated at the level of the oil sands after installation by a perforator provided for this purpose. It is sometimes desirable to perforate the water string also, as when the latter has been cemented off below the oil bearing strata which it is desired to drain, and it is inconvenient or impossible to raise the lower end of the water string to this strata.

It is an object of my invention to provide a novel casing perforator adapted to perforate one or more casings, and likewise, the cement around the water string before communication is established between the oil string and the oil bearing strata.

Since those perforators now in use are not adapted to give the operator a positive indication of the completion of the perforation, the operation oftentimes continues until the perforations are in the form of long slits which materially weaken the casing and decreases the efficiency of the straining action.

It is another object of my invention to provide a perforator of the class described which will give a positive indication to the operator when the casings have been perforated.

In the casing perforator shown in my application Serial No. 256,178, referred to heretofore, much trouble is had with the breaking of the cutter blade of the perforator. When the blade is forced into the casing to be cut, it is moved outward and tends to pivot around the upper gripping portion which engages the casing. Since the blade is inclined upward and inward the upper face of

the blade engages the upper edge of the slot being formed. At this time there is a down force on the blade where it engages the upper edge of the slot, tending to move the blade downward, but this downward movement is resisted by the engagement of the gripping portion and the casing. Either of two actions will occur—the casing will be torn at the upper end of the slot being formed or the blade will break. My experience has been that the blade will break after a few slots have been cut.

It is one of the important objects of my invention to provide a casing perforator in which the cutter is free to move vertically; that is, to move along the casing as the blade is forced through the casing so that the cutter may be moved or guided by the blade in order that shearing strains in the blade will be eliminated.

A still further object of my invention is to provide a casing perforator in which the cutter engages the casing adjacent the place where the blade thereof is cutting the slot, and in which friction reducing means is provided at the engagement point of the cutter and the casing, so that the cutter is free to move up or down as the blade is being forced outward or moved inward relative to the casing.

A still further object of my invention is to provide friction reducing means in the form of roller means.

It is a further object of my invention to provide a casing perforator with a cutting member having friction reducing means so that the body may move as guided by the blade portion in order to reduce shearing strains in the cutting member.

A further object of my invention is to provide a perforator in which the cutting member may be moved into cutting position at any time it is desired and which will not move into cutting position while the perforator is being extended downward in the casing.

It is still another object of the invention to provide a perforator as described which can be easily pulled from the casings.

Further objects and advantages will be made evident in the following description il-

lustrated by the accompanying drawings, in which:

Fig. 1 is an enlarged vertical section of the perforator of my invention with the cutter member in retracted position.

Fig. 2 is a vertical section similar to Fig. 1, except that the cutter member is released and in cutting position.

Fig. 3 is an enlarged cross-sectional view indicated by line 3—3 of Fig. 1.

Fig. 4 is a vertical section of part of the body portion of my perforator showing the position of the cutter at the completion of the perforation.

Fig. 5 is a detailed enlarged perspective view of my perforator cutter detached from its operative mechanism.

Fig. 6 is a fragmentary view of Fig. 1, showing an alternative type of cutter with one large guide roller and showing two different positions of the cutter element.

Fig. 7 is a fragmentary sectional view showing the lock means provided on the cutter actuating device.

Referring to the drawings and particularly to Fig. 1, an outer casing or water string 10 has been inserted in a well and is cemented off at its lower end in the usual manner. The upper end of the casing 10 is provided with a casing head not illustrated, forming a tight fit between the water string 10 and an oil string 11 which is extended inside the water string. When it is desired to permit oil to flow into the oil string 11 at a level above that at which the water string is cemented off, as at an oil stratum, a perforator 12 of my invention is attached to the lower end of a jar and lowered on a cable through the oil string 11 in the ordinary manner. The jar and weight mechanism connected therewith may be of the conventional type known in the art, comprising two interlocking links with a ram or weight attached to the upper link.

The perforator 12 includes a body 13 cylindrical in cross-section, as illustrated in Fig. 3 with a coupling 14 at its upper end adapted to threadedly receive the lower end of a link of the jar mechanism not illustrated. The lower end of the body 13 has a cylindrical hub 15 of lesser diameter than the body 13, and this hub is provided with external threads 16 for a purpose to be described later.

Formed diametrically in the body 13 and with its axis parallel to the axis of the perforator 12 is a cutter slot 17 having a vertical, an inclined, and an arcuate wall, as indicated by the numerals 18, 19, and 20 respectively in Figs. 1, 2, 4, and 6. At right angles to the cutter slot 17 a cam slot 21 extends through the body 13, this cam slot comprising a portion 22 and a portion 23 substantially parallel to the vertical wall 18 and the inclined portion 19 of the cutter slot 17.

Positioned in the cutter slot 17 is a cutter

element 24 non-rotatably mounted on a cutter shaft 25 slidably disposed in the cam slot 21, the cutter shaft 25 being of a length which prohibits its projection outside the body 13 at any position in the cam slot 21 for obvious reasons. The cutter element comprises a rectangular body portion 26 and a blade 27 disposed at approximately right angles to the body portion. The blade 27 is provided with a lower edge 28 and a forwardly curved cutting edge 29 forming a continuation of the edge 28. The cutter element en bloc is preferably forged from relatively hard metal and the body portion thereof is provided with flat sides 30 and 31 and flat edges 32 and 33. The blade 27 is centrally disposed on the edge 33 at the lower end and thereby forms with the body 26 the shoulders 34 at the opposite sides of said blade. A flange 35 is centrally disposed on the edge 32 of the body portion 26 and forms with the said body the oppositely disposed shoulders 36. The shoulders 36 adjacent the base of the cutter body diverge inwardly towards the shoulders 34 and form a stop 37. The flange 35 extends from a point adjacent the upper end of the edge 32 of the body portion and gradually tapers outwardly and increases in thickness towards the lower end of the body portion as at 38 and then inwardly, the lower surface thereof merging into the lower edge 28 of the blade 27.

The upper end of the body portion of the cutter element 24 is bifurcated for the reception of upper and lower friction rollers 39 and 40, the upper rollers 39 being mounted on a stub shaft 41 having bearings in bosses 42 formed on the outer edge portions of the bifurcations 43 and 44, while the lower friction roller 40 is mounted below but in advance of the roller 39 on a stub shaft 45 having bearings in the bifurcations 43 and 44. Resultant of mounting the upper roller 39 in the bosses 42, the same is projected forwardly of the flange 35 and upwardly from the bifurcations 43 and 44. The roller 40 projects outwardly from the bifurcated portions 43 and 44 on the edge 33 and is adapted for engagement with the inner surface of the casing 11.

The cutter element 24 is so mounted on the cutter shaft 25 as to permit the flange 35 to fit within a groove 46, Figs. 3 and 4, formed in the rear wall of the cutter slot 17 and the shoulders 36 of the cutter to slide upon the oppositely disposed shoulders 47 formed resultant of the placement of said groove 46.

The external threads 16 of the cylindrical hub 15 are adapted to screw into internal threads of a hollow cylindrical sleeve 48 of a trip cage 49. Threadedly secured in the lower end of the sleeve 48 is an end plate 50 with a central cylindrical bore 51 through which a trip shaft 52 is adapted to slidably extend.

Retained in threaded engagement with the upper end of the trip shaft 52 as by a lock nut 130

53 is a trip plate 54. Slidably disposed in a cylindrical bore 56 in the body 13 of the cutter 12 which communicates with the cutter slot 17, is an operating pin 55. The operating pin 55 is provided with a hub 57 at its lower end and a head 58 at its upper end, both of which are of greater diameter than the bore 56 so that the movement of the pin in the bore is limited.

10 Referring particularly to Figs. 1 and 7, the trip plate 54 carries a pin 75 which projects outward into a slot 76 carried by the tube 48. The upper end of the slot which is indicated by the numeral 77 is so located that when the pin 75 rests in the slot the trip plate 54 is prevented from moving upward in the tube 48, and consequently cannot move the operating pin 55 upward. The lower end of the slot 76 is open at 78 and below the slot is an inclined wall 79. When the trip plate 54 is moved downward to the bottom end of the slot 76 the pin 75 will engage the inclined wall 79, thus causing the trip plate to rotate relative to the tube 48. This will move the pin 55 from the lower end of the slot 78 so that when the body 12 is subsequently lowered the pin 75 will not prevent the trip plate 54 from moving upward into the position shown in Fig. 2, in which position the operating pin 55 is elevated so as to operate the perforator cutter.

Threadedly secured to the lower end of the trip shaft 52 is a cylindrical stop member 59 slidably disposed in a cylindrical sleeve 60 which is threadedly attached at its lower end to a spring-retaining shaft 61. Disposed between the cylindrical stop member 59 and the spring-retaining shaft 61 in the cylindrical sleeve 60 is a coil spring 62 which acts as a shock absorbing member for the trip shaft 52. It should be obvious that the trip shaft 52 is free to rotate relative to the spring-retaining shaft 61. Attached as by screws 63 are flat springs 64 here shown fragmentary, the said springs being preferably four in number, adapted to frictionally and resiliently engage the inner surface of the oil string 11.

55 The operation of my invention is as follows:

The cutter is placed in the position shown in Fig. 1 and the apparatus with its associated jar and weight is lowered by the cable into the oil string 11 to the level at which it is desired to perforate the casings.

When the apparatus is at the level at which it is desired to operate the cutter, the cable is subjected to an upward pull. Because of the engagement of the flat springs 64 with the casing 11, this causes a relative movement between the body 13 and the spring-retaining shaft 61 so that the spring-retaining shaft 61, the trip shaft 52, and the trip plate 54 move downwardly relative to the body 13. When the trip plate moves to the lower end of the

tube 48 the pin 75 engages the inclined wall 79, causing the trip plate and shaft 52 to rotate relative to the body 12 and the tube 48. This moves the pin 75 from alignment with the slot 76. When the body and associated parts are then lowered the trip plate 54 is free to move upward into such a position that the operating pin 55 will be actuated. When the operating pin 55 is actuated by raising it the head 58 thereof engages the lower edge of the blade 27 and swings the cutter on its pivot so that the blade is moved into engagement with the casing to be perforated, as shown in Fig. 2.

15 As the weight is raised and dropped by the cable the cutting edge 29 of the cutter blade 27 is forced into the casing 11. Each successive blow on the perforator causes the cutter to move upward relative to the body 13 in the cam slot 21. Because of the inclined portion 23 of the cam slot 21 this relative movement forces the cutter blade 27 further into the casing 11. The roller 40 on the cutter element engages the inner surface of the casing 11 to retain the blade portion 27 in proper cutting position. The pounding action is continued until both casings and the formation immediately adjacent are perforated. It should be noted that because of the fact that the cutter 24 is operating through a circular swing, the cutter blade has an exceptionally long throw so that any cement or non-porous formation adjacent to the outer casing can also be perforated.

20 When the cutter blade 27 has finished the perforation, the cutter shaft 25 will be at the top of the inclined portion 23 of the cam slot 21 as illustrated in Fig. 4. At this time the body 13 and jar and weight will drop until the cutter shaft 25 reaches the top of the vertical portion 22 of the cam slot 21, thus giving the operator a positive indication of the completion of the perforation.

25 The perforator 12 is then pulled upward, the cutter shaft 25 sliding in the inclined portion 23 of the cam slot 21 and removing the cutter blade 27 from the perforation. The frictional engagement of the flat springs 64 with the casing 11 causes the spring-retaining shaft 61, the trip shaft 52 and the trip plate 54 to move downward relative to the body 13 when the whole apparatus moves upward as a unit.

30 The downward movement of the trip plate 54 relative to the body 13 permits the operating pin 55 to assume the position shown in Fig. 1 so that the movement of the cutter shaft 25 in the inclined portion 23 of the cam slot 21 may continue until the cutter 24 assumes the position shown in Fig. 1, in which it offers no resistance to the upward movement of the perforator. This upward movement of the apparatus is continued until that level is reached at which another perforation is made. The cutter 24 is moved into operat-

ing position in this second location by simply lowering the weight. The flat springs 64 retain the trip plate 54 in the same position while the body 13 is lowered until the trip plate 54 causes the operating pin 55 to move the cutter 24 into cutting position. Thereafter the operation is identical with that already described.

It will be noted that when the blade has been brought into engagement with the casing to be perforated and when the body is lowered there will be a relative vertical movement between the cutter and the body. By reason of the inclined portion of the slot the entire cutter will be moved outward from the body and the cutter will be so swung that the blade and the anti-friction means in the form of the roller 40 both engage the casing. Upon further downward movement of the body 13 the inclined slot 19 operating on the pin 25 exerts a force against the cutter which tends to pivot it around the anti-friction means 40. The blade 27 therefore is caused to penetrate the casing. In view of the fact that the blade when it starts its cutting operation is inclined and is higher at its inner end than at its outer end, as the blade is forced inward, the upper face of the blade engages the upper wall of the slot being formed and as the outward or cutting movement of the blade continues, this pressure becomes greater due to the fact that the blade is inclined. When the pressure of the upper face of the blade against the upper wall of the slot being formed reaches a certain amount the entire cutter will move downward so that the blade may pass through the opening being formed without tearing the upper wall of the slot being formed, and preventing excessive shearing strains from being placed on the blade. It will therefore be seen that the anti-friction means not only acts as a fulcrum for the cutter but in addition acts as a means which permits the cutter to move vertically and acts as a means which permits the cutter to be guided by the blade as it passes through the slot being formed. When the casing is perforated, as shown in Fig. 4, the upper face of the blade 27 is in substantially a horizontal position. It has reached this horizontal position not by the lower portion or the outer portion of the upper edge when in the position shown in Fig. 1 moving upward to the level of the upper portion or inner portion of the upper edge but by the cutter moving bodily downward so that the blade 27 will pass through the perforations without tearing away the upper end of the perforation and without placing excessive strains on the blade which would result in a breakage. When the cutter 24 has assumed the position illustrated in Fig. 4, the roller 39 engages with and rotates on the rear wall of the groove 46 and takes up the friction encountered by it with the body 13.

In the modification illustrated in Fig. 6,

the construction is the same as in the preferred form, with the exception, that a single relatively large roller 61^a on the cutter element 62 takes the place of the two rollers 39 and 40. In this form the roller 61^a functions to reduce the friction by engaging at one side the inner surface of a casing 63^a and at the other side the inner wall of a groove 64^a in the cutter slot 65. In this form the cutter element 62 is likewise formed with a blade 66.

In this manner a direct long thrust is imparted to the cutter blades 27 and 66. Likewise, a resultant of the use of the rollers 39, 40 and 61^a, the friction which would normally be encountered between the upper part of the cutter body and the casing wall and the perforator body, is taken up by the rollers. It is likewise obvious, that resultant of the novel construction and mounting of the cutter element in the perforator body the shearing stress on the blade member is minimized and consequently the shearing or breaking off of the cutter blades is prevented.

While the preferred forms of embodiment of my invention above illustrated and described are fully capable of fulfilling all of the purposes primarily stated, I do not wish to be specifically limited to them, for it is to be understood that my invention may be embodied in various other forms, all coming within the scope of the claims which follow.

I claim as my invention:

1. In a casing perforator, the combination of: a body; a cutter carried by said body and movable relative to said body, said cutter having a blade adapted to penetrate a casing, and engaging means adapted to engage said casing near the place where said blade penetrates said casing, said engaging means permitting said cutter to move along said casing and to be guided by said blade as it moves through said casing; and operating means whereby said cutter is operated by said body.

2. In a casing perforator, the combination of: a body; a cutter carried by said body and movable relative to said body, said cutter having a blade adapted to penetrate a casing, and roller means adapted to engage said casing near the place where said blade penetrates said casing, said roller means permitting said cutter to move along said casing and to be guided by said blade as it moves through said casing; and operating means whereby said cutter is operated by said body.

3. In a casing perforator, the combination of: a cutter having a blade adapted to penetrate a casing, and fulcrum means adapted to engage said casing adjacent to said blade, said fulcrum means being designed to permit relative movement of said cutter along said casing; and mechanism for forcing said cutter outward against said casing around said fulcrum means, said blade being caused to

penetrate said casing, said fulcrum means moving along said casing as said blade moves through said casing.

4. In a casing perforator, the combination of: a cutter having a cutter body, a blade extending at an angle to said body and a fulcrum means on said cutter body adapted to engage said casing adjacent to said blade, said fulcrum means being designed to permit relative movement of said cutter along said casing; and mechanism for forcing said cutter outward against said casing around said fulcrum means, said blade being caused to penetrate said casing, said fulcrum means moving along said casing as said blade moves through said casing.

5. In a casing perforator, the combination of: a cutter having a blade adapted to penetrate a casing, and roller means adapted to engage said casing adjacent to said blade, said roller means being designed to permit relative movement of said cutter along said casing; and mechanism for forcing said cutter outward against said casing around said roller means, said blade being caused to penetrate said casing, said roller means moving along said casing as said blade moves through said casing.

6. In a casing perforator, the combination of: a cutter having a cutter body, a blade extending at an angle to said body and a roller means on said cutter body adapted to engage said casing adjacent to said blade, said roller means being designed to permit relative movement of said cutter along said casing; and mechanism for forcing said cutter outward against said casing around said roller means, said blade being caused to penetrate said casing, said roller means moving along said casing as said blade moves through said casing.

7. In a casing perforator, the combination of: a shell having a cutter receiving cavity; a cutter in said cavity, said cutter having a body and a blade extending therefrom; operating means connected to the lower part of said body and to said shell whereby said cutter is operated so that said blade penetrates a casing; and friction reducing means at the upper end of said body for engagement with the bottom of said cavity.

8. As a new article of manufacture, a cutter for a casing perforator consisting of: a body; a blade extending from said body at an angle thereto; and means associated with said body for reducing the friction between said body and the casing being perforated, said means tending to move said blade into cutting engagement with said casing.

9. As a new article of manufacture, a cutter for a casing perforator consisting of: a body; a blade extending from one end of said body at an angle thereto; and means associated with said body for reducing the friction between said body and the casing being perforated, said means tending to move said

blade into cutting engagement with said casing.

10. As a new article of manufacture, a cutter for a casing perforator consisting of: a body; a blade extending from said body at a right angle thereto; and means associated with said body for reducing the friction between said body and the casing being perforated, said means tending to move said blade into cutting engagement with said casing.

11. As a new article of manufacture, a cutter for a casing perforator consisting of: a body; a blade extending from said body at an angle thereto; and a roller associated with said body for reducing the friction between said body and the casing being perforated, said roller tending to move said blade into cutting engagement with said casing.

In testimony whereof, I have hereunto set my hand at Los Angeles, California, this 15th day of November, 1928.

DANIEL L. SHULL.
